—Inventor;
Ira W. Nonneman,

By Bales & MacKlin, Attys.

UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

PIPE-CUTTER.

1,282,619.

Specification of Letters Patent.

Patented Oct. 22, 1918.

Application filed February 2, 1918. Serial No. 215,015.

To all whom it may concern:

Be it known that I, IRA W. NONNEMAN, a citizen of the United States, residing at Warren, in the county of Trumbull and State of Ohio, have invented a certain new and useful Improvement in Pipe-Cutters, of which the following is a full, clear, and exact description, reference being had to the accompanying drawings.

10 This invention relates to pipe cutters, having the knife fed to the work by a spring pressure, thus avoiding the periodic screw feeding of the knife and the consequent irregularity in the cut, and enabling the cutter to make a clean cut through the pipe simply by the continuous rotation of the tool. The object of the invention is to provide such a tool in a form which shall be simple in construction, in which the spring 15 shall be effectively housed, and clogging by chips is avoided. The invention is herein-after more fully explained in connection with the accompanying drawings, and the essential characteristics are set out in the 20 claims.

25 The drawings illustrate the invention embodied in a duplex cutter. Figure 1 is an edge view of such a cutter; Fig. 2 is a side elevation thereof; Figs. 3, 4 and 5 are sections on an enlarged scale through one of the housings for the spring and knife—Fig. 3 being sectioned in a plane parallel with Fig. 2, Fig. 4 in a plane parallel with Fig. 1, and Fig. 5 being a transverse section 30 indicated by the line 5—5 on Fig. 4. Fig. 35 6 is a fragmentary elevation on the same scale with Fig. 2 and looking from the opposite direction and showing the guide blocks in working engagement.

40 As shown, the frame of the cutter consists of two stationary end brackets 10 and 11 and a rigid connection between them consisting of two parallel bars 12 and 13 rigidly connected to the brackets, as by rivets shown 45 at 14 and 15. 20 indicates a movable bracket which has a tongue 21 extending into the space between the bars 12 and 13 and guided in that space by reason of a groove in one side of the tongue which is occupied by a 50 key 16 seated in the bar 13.

In the construction shown, the movable bracket is put in place before the rivets 14

and 15 are secured, and then the upsetting of these rivets effectively retains the parts in place. This particular construction of 55 pipe-cutter frame is not claimed herein, but in my pending application No. 147,420, filed February 8, 1917.

Each of the brackets 10 and 20 carries or is formed into a housing for the pipe guide, 60 knife and feeding spring, as hereinafter more fully explained. The guide 50 and knife 40 are brought into engagement with a pipe (as for instance, the pipe A in Figs. 1 and 2) by the rotation of a screw 30, which 65 is threaded in the bracket 11 and has a swivel connection at 31, Fig. 4, in a boss 27 formed on the movable bracket 20.

The bracket 10 carries a socket 18 for the reception of the handle 19, but with the exception of the external connections the two brackets or housings 10 and 20 are identical and therefore the description of the housing 20, as shown particularly in Figs. 3, 4 and 5, will apply equally well to the stationary housing 10.

As shown in Figs. 3, 4 and 5, the housing 20 comprises a rectangular box having a base or back 25, side walls 26 and an end portion 27 in which the end of the screw 30 80 is swiveled. A cover plate 55 rests on the walls 26 and extends at 56 over their outer ends into close engagement with the boss 27. This cover is shown as secured by screws 57.

Inclosed within the housing and slidably 85 engaging its walls and base and cover 55 is a block 44 which has a cylindrical recess 45 in which seats a helical spring 48 compressed between the base of the recess and the boss 27 of the housing. The knife 40 90 is rigidly secured to the block 44 as by screws 46 extending through the knife. This knife is located just behind an opening 58 in the cover plate, so that the screws are readily accessible and the knife may be removed through such opening. However, the edge of the knife comes close enough to the edge of the opening so that no chips can work around the knife into the interior of the housing.

The guide 50 which engages the pipe and positions the tool consists of a strong plate having a V-shaped groove 51 and rigidly secured to the end walls 26 of the housing

as by screws 52. This plate, therefore, has the double function of acting as the pipe guide and as the end closure of the housing.

The plate is reinforced on the inner side 5 by the boss 53, and the slidable block 44 is correspondingly recessed at 49 to receive the boss, and has its end inclined corresponding to the incline of the inner face of the plate 50, as shown in Fig. 4.

10 The construction described makes the end plate very strong to resist the strain if the tool be screwed tight on a pipe. The slid- 15 able block has a sufficient size to be easily and accurately guided by the inner faces of the housing. At the same time the construction is compact, and the housing may be comparatively small.

When the tool stands idle, the extended spring 48 maintains the block 44 resting 20 against the inner face of the pipe guide 50. This position holds the cutting edges of the knife a considerable distance nearer the axis of the pipe than the pipe guides 50. When the tool is put to work, the screw 30 25 is turned (as, for instance, by the handle 32) feeding the housing 20 toward the housing 10. As the knives 40 engage the pipe they are forced back, the springs 48 being compressed as the housings continue to approach each other. This unseated position 30 of the tool is illustrated in Figs. 1 and 2, where the knives have engaged the pipe; but the housings have not yet been brought together close enough for operation.

35 When the pipe guides 50 are brought into engagement with the pipe by the continued approach of the housings, as shown in Figs. 3, 4 and 6, the device is ready for operation. During the operation, all that is necessary 40 is to turn the tool about the axis of the pipe, as the cutters are continuously fed into the pipe by the action of the springs 48. It should be noted that each cutter has a cutting edge 41 and a stopping shoulder 42 45 which limits the cutting action and prevents the knife digging into the pipe faster than it can cut.

Whenever it is desired to remove the knives for sharpening, or to substitute other 50 knives, this is easily accomplished by taking out the screws 46, the knife being readily removable through the opening 58. By having the pipe guide in the form of a solid block 50 rigidly carried by the housing, I obtain an accurate guiding of the tool 55 on the pipe, while by using the guide support as an inclosing housing for the spring and the sliding block which carries the knife, I prevent any clogging by dirt or 60 chips getting on the sliding surface along which the block moves. Making the end members of the housings the pipe guides, renders the tool more compact and of an easier shape to carry and handle than if 65 the guides were extended on the side. Ac-

cess to the interior of the housing may be had whenever necessary by removing the screws 52.

Having thus described my invention what I claim is:—

70 1. In a tool of the character described, the combination, with a frame, of a housing carried thereby, a block within the housing slidable therein, a spring acting on the block, said housing having an end closure which 75 forms also a guide for the pipe, and a knife carried by the housing.

2. In a pipe cutting tool, the combination of a frame, means carried thereby for engaging the pipe on one side, a box-like housing mounted on the frame, a block movable within the housing, a knife carried by said block at one side thereof, and a spring within the housing forcing the knife toward the pipe, there being a rigid end member 85 for the housing alining with the block and forming also a guide for the pipe, said end member and knife being adapted to engage the pipe on the side opposite to that first mentioned.

90 3. In a tool of the character described, the combination, with a frame, of a housing carried thereby, a block within the housing slidable therein, a spring acting on the block, an end closure for the housing forming also 95 a guide for the pipe, said end closure being formed with a V-shaped groove in its exposed face, and a knife secured to the internal block and overhanging the edge of the end closure.

100 4. In a tool of the character described, the combination, with a frame, of a housing rigidly carried thereby, a housing slidably carried thereby, each housing having an end closure adapted to form a pipe guide and 105 having an internal block, a spring in each housing pressing the block toward the pipe, and a knife secured at the side of each block and adapted to engage the pipe.

110 5. In a tool of the character described, the combination with a frame, of a housing carried thereby, an end member for the housing having a V-shaped groove in its outer face and a reinforcing boss on its inner face, a slid- 115 able block within the housing having a recess to receive such boss, a spring acting on the block, and a knife at the side of the housing secured to the block.

120 6. In a tool of the character described, the combination, with a frame, of a housing carried thereby, an end member for the housing having a V-shaped groove in its outer face, a slid- 125 able block within the housing having a recess in its outer face, a spring within the housing seating in the recess of the block, and a knife secured to the block.

130 7. In a tool of the character described, the combination with a frame, of a housing carried thereby and comprising a back portion and side walls, an end member for the hous-

ing formed to act also as a pipe guide, a block slidable within the housing, a spring acting on the block, a knife removably secured to the block, and a cover plate for the face of the housing having an opening through which the knife securing devices are accessible.

8. In a tool of the character described, the combination, with a frame, of a housing rigidly carried thereby, a housing slidably carried thereby, each housing comprising a back portion and side walls and an end member having a V-shaped outer face to act as a pipe guide, a block slidable within each housing, a spring acting on each block, a knife removably secured to each block, a cover plate for the face of each housing having an opening through which the knife-securing devices are accessible, and means for moving the slidable housing toward or from the rigid housing.

9. In a tool of the character described, the combination, with a frame, of a box-like hollow housing carried thereby and having

parallel walls, a block within the housing 25 slidably guided by said walls, a knife secured to the side of the block, and a plate held against ends of the housing walls and forming a closure for the housing and serving also as a guide for the pipe.

10. In a tool of the character described, the combination, with a frame, of a housing carried thereby and comprising a rectangular box having rigid side walls and an end adapted to be opened, a plate normally closing said end and secured to the side walls and having a V-shaped groove in the outer face adapted to constitute a pipe guide, a block slidable within the housing and engaging the side walls thereof, a spring within 40 the housing bearing against said block, and a knife secured to the side of the block and extending across the edge of the end plate and adapted to engage the pipe.

In testimony whereof I hereunto affix my 45 signature.

IRA W. NONNEMAN.
